UNITED STATES PATENT OFFICE

ANDREW L. COURTER, OF PATERSON, NEW JERSEY, ASSIGNOR TO C. K. EAGLE & CO., INC., OF NEW YORK, N. Y., A CORPORATION OF PENNSYLVANIA

DESIGN FOR A DECORATIVE FABRIC

Application filed June 23, 1930. Serial No. 36,142. Term of patent 3½ years.

To all whom it may concern:

Be it known that I, ANDREW L. COURTER, a citizen of the United States, residing at Paterson, county of Passaic, and State of New Jersey, have invented a new, original, and ornamental Design for Decorative Fabrics, of which the following is a specification, reference being had to the accompanying drawing, forming part thereof, in which the figure is a plan view of the decorative fabric showing my new design.

I claim:

The ornamental design for a decorative fabric as shown.

ANDREW L. COURTER.
